TORPEDO

Maury I. Hull, Arlington, Va.

Application October 17, 1940, Serial No. 361,640

17 Claims. (Cl. 114—23)

The invention relates particularly to torpedoes which are guided by sound waves.

A principal object of my invention is to provide a torpedo which will have general utility, and which may be dropped from a parachute near an enemy vessel, or may be fired from a torpedo tube, or may be launched by dropping overboard from the deck of a surface vessel, or may be moored at any desired point, where it will wait until a vessel comes within range of its sound apparatus, when it will release itself from its mooring, and proceed toward its target.

A further object of my invention is to provide a torpedo which may be launched without respect to aim, and which when launched will select its target from any point on a 360 degree horizon.

A further object of my invention is to provide a torpedo which may be launched by parachute from aircraft.

A further object of my invention is to provide a torpedo which can move in a vertical plane, and seek out submarines coming within range of its sound apparatus.

A further object of my invention is to provide a torpedo which may be moored at a stationary point until a sound target comes within range, when it will release itself from its mooring and proceed toward its target.

A still further object of my invention is to provide a system whereby the torpedo control apparatus is able to discriminate between various sounds reaching its microphones.

A still further object of my invention is to provide apparatus responsive to sound waves for detaching the parachute from the torpedo.

A still further object of my invention is to provide apparatus responsive to light waves for rendering the torpedo inoperative.

Still a further object of my invention is to provide a discriminating mechanism to control the manner in which light may affect the torpedo.

Still a further object of my invention is to provide a discrimination mechanism responsive to radiant energy for rendering the torpedo temporarily inoperative so that friendly vessels may pass unharmed within range.

Other objects of my invention will appear after a consideration of the following description taken in connection with the accompanying drawings, in which:

Figure 1 is a diagram showing the electrical circuits actuated by the microphones which con-

trol motion in the horizontal and vertical planes, and the electrical circuits which control the steering apparatus.

Figure 2 is a diagram showing the light sensitive circuit, the "listening" microphone, and the sound discriminating circuit.

Figure 3 is a radio control circuit.

Figure 4 is an illustration of the various arcs from which the four microphones shown in Figure 1 controlling the motion in the horizontal plane will respond to sounds, arcs I, II, III, and III corresponding to microphones 1, 2, 3, and 4 respectively.

Figures 5 and 6 are external views showing the location of the various microphones on the outside of the torpedo, and the rudders.

Figures 7 and 8 are sectional views of the rear portion of the torpedo showing the steering apparatus in more detail.

Figure 9 is a view of the arrangement of the various parts of the torpedo.

Figures 10, 11, 12, and 13 are views of the mechanism by which the parachute is attached to the torpedo, and the mechanism for releasing it when the torpedo reaches the surface of the water.

Figures 14 and 15 are illustrations of the mooring of the torpedo, and the mechanism for releasing it.

Figure 16 is a sectional view of the fuse of the torpedo, and the mechanism for rendering it temporarily inoperative.

Referring to Figure 1, microphones 1 and 2, located near the front or head of the torpedo (Figure 5), excite thermionic tubes 11 and 12 respectively, which are biased by battery 31. The plate circuit of tube 11 includes resistance 101, battery 51, and the audio filter consisting of choke 41 and condenser 42. The plate circuit of tube 12 includes resistance 102, battery 52, and the audio filter consisting of choke 41 and condenser 42. Tube 11 is coupled to tube 21 by coupling condenser 91, and bias is supplied to tube 21 through resistance 111 by battery 61. Tube 12 is coupled to tube 22 through condenser 92, and bias is supplied to tube 22 through resistance 112 by battery 62. Battery 71 supplies the plate potential to both tubes 21 and 22, the plate currents of the two tubes flowing through separate windings of the double polarized relay 20, and the combined plate currents of tubes 21 and 22 flowing through the winding *m* of differential relay 30.

Microphones 1 and 2 are identical, except that their patterns of response are directed to differ-

ent arcs as shown in Figure 4. Tubes 11 and 12, tubes 21 and 22, resistances 101 and 102, batteries 51 and 52, batteries 61 and 62, and resistances 111 and 112 are identical or of equal characteristics or values, so that when sounds reach microphones 1 and 2 in equal intensities, the plate currents of tubes 21 and 22 are equal.

The double polarized relay 20 has two windings. The plate currents flow through these windings in opposite directions, so that the magnetic fields tending to be set up as a result of the currents oppose each other, with the result that when the two plate currents are equal, the resulting magnetism is zero, and neither contact of the relay closes. The two armatures of the relay are permanently magnetized, so that they will be attracted to their respective ends of the core only when the poles of the relay core are of the proper polarity. As a result of this, only contact *a* will close when the plate current of tube 21 exceeds that of tube 22, and only contact *b* will close when the plate current of tube 22 exceeds that of tube 21.

Contact *a* of relay 20 when closed energizes magnet 18 through battery 81. Contact *b* of relay 20 when closed energizes magnet 17 through battery 81.

Refer now to Figures 5 and 6, showing top and side views respectively of the torpedo, with the rudder 98 controlling motion in the vertical plane, hereafter to be called the vertical control rudder, and the rudder 107 controlling motion in the horizontal plane, hereafter to be called the horizontal control rudder.

Refer next to Figures 7 and 8 which show side and top sectional views respectively of the rudder control mechanisms. In Figure 8, magnet 18 when energized pulls rudder arm 116 toward it, moving rudder 107 (Figure 7) so that the torpedo if moving forward turns toward the right. Magnet 17 when energized pulls rudder arm 116 toward it, tending to turn the torpedo toward the left. The rudder arm is normally held in a "straight ahead" position by springs 117 and 118. The propeller shaft passes above this portion of the rudder control mechanism, as shown in Figure 7. In Figure 8, the vertical control rudder 98 is moved by rudder arm 115. Magnets 8 and 10 when energized pull the rudder arm down, making the torpedo turn downward. Turning again to Figure 7, magnet 9 when energized pulls the rudder arm up, turning the torpedo upward. Rudder arm 115 is normally held in a "straight ahead" position by springs 109 and 110. Magnet 7 shown in Figure 1 as being energized at the same time as magnet 9 is not shown in either of the sectional views for the sake of clearness, but would occupy a position parallel to and back of magnet 9 in Figure 7, and directly over magnet 8 in Figure 8.

Returning to Figure 1, if the microphones 1 and 2 and associated apparatus are identical or balanced, when the sounds reaching the two microphones are equal in intensity, the plate currents of tubes 21 and 22 will be equal, and neither contact of relay 20 will close. But if the sound reaching microphone 1 is greatest, contact *a* of relay 20 closes, energizing magnet 18, and making the torpedo turn to the right, while if the sound reaching microphone 2 is greater in intensity, contact *b* of relay 20 closes, energizing magnet 17, turning the torpedo toward the left. For example, if the torpedo is moving directly toward its target, and the target then moves so that it is slightly to the right of the torpedo's direction of motion, the sound reaching microphone 1 will become slightly

greater in intensity than that reaching microphone 2, with the result that magnet 18 is energized, turning the torpedo toward the right until it is again pointed directly at the target, at which time the sound reaching microphones 1 and 2 again becomes equal, contact *a* of relay 20 opens, and the torpedo straightens out. Had the target moved toward the left of the line of motion, magnet 17 would have been energized as explained above, and the torpedo turned toward the left. In this way, the torpedo is kept pointed directly at the source of sound, which is the only direction of motion which will permit the sound to reach microphones 1 and 2 in equal intensity.

15 In Figures 5 and 6, a second pair of microphones 3 and 4 shown, placed on the torpedo. In Figure 1, these microphones 3 and 4 excite tubes 13 and 14 respectively, which are biased by battery 33. The plate of tube 13 is coupled to the grid of tube 20 23 in a manner similar to that described in the case of tubes 11 and 21, and tube 14 is similarly coupled to tube 24. Batteries 63 and 64 may bias tubes 23 and 24 at cut-off respectively. Assuming switch 216 closed, the combined plate currents of tubes 23 and 24 flow through winding *n* of differential relay 30. This relay is so designed that as long as the current in winding *n* exceeds that in winding *m*, the relay contacts will remain closed. When the current in winding *n* equals or falls below that in winding *m*, the contact *c* is broken. This is to say that as long as the sum of the plate currents of tubes 23 and 24 exceeds the sum of the plate currents of tubes 21 and 22, the contacts are closed at *c*. When the contacts at *c* are closed magnet 17 is energized through battery 81, moving the torpedo toward the left.

The switch 216 is provided in the plate circuits of tubes 23 and 24 to break the circuit of winding *n* when opened. The purpose of this switch will 40 be disclosed subsequently.

Refer now to Figure 4, which shows the directional characteristics of the microphones 1, 2, 3, and 4, the arcs of response I, II, III and IIII belonging to the microphones respectively. The patterns of response of the various microphones are not uniform within their respective arcs, but the microphones have their maximum sensitivity to sounds approaching from the center of the arc, the sensitivity falling off uniformly on each side of the center until it reaches zero or approaches zero at the boundaries of the arcs shown by the dotted lines. These directional characteristics may be obtained by the desired shaping of an acoustical horn or sound chamber used to conduct sound to the diaphragm, or the directional characteristic might be inherent in the design of the microphone itself. The arcs of response of all of the microphones overlap at both ends.

Suppose now that the torpedo is launched from an airship, and lands so that the sound of its target approaches from the middle arc III. In that event, microphones 1 and 2 will not be excited, but microphone 3 will, hence more plate current will flow through winding *n* of relay 30 than will flow through winding *m*. Contact *c* will close, exciting magnet 17, causing the torpedo to turn in a counter-clockwise direction (Figure 4), or in other words, turn left. It will continue to turn in this direction until the sound approaches from arc IIII. From this direction, also, microphones 1 and 2 are not excited, but the excitation of microphone 4 causes the current in winding *n* of relay 30 to exceed that in winding *m*, so that contact *c* remains closed, and the torpedo continues to turn left or counter-clockwise. It will

continue to turn until the point Z on the arcs is reached, which point is included in both arcs II and III. From this point the sound reaches both microphones 2 and 4. The plate current begins to rise in winding m of relay 30 due to the excitation of microphone 2 and tubes 12 and 22. Motion will continue in a counter-clockwise direction until the plate currents of windings m and n are equal, de-energizing the relay 30, and breaking contact c. But at this moment when contact c of relay 30 breaks, contact b of relay 20 closes, for microphone 2 is being excited while microphone 1 is not, and because the plate current in one winding of relay 20 due to the current in tube 22 exceeds that in the other winding of relay 20. As previously explained, when the plate current of tube 22 exceeds that of 21, only contact b closes. When contact b closes, it excites magnet 17, turning the torpedo left or counter-clockwise. It continues to turn until point Y is reached, that is, until the sound comes from the direction of Y. At this point, the sound reaching microphones 1 and 2 is equal, and contact b opens due to the de-energization of double polarized relay 20, as previously explained.

Resistances 103 and 104 are made variable so that the plate currents of tubes 23 and 24 may be adjusted in relation to the plate currents of tubes 21 and 22.

Motion in the vertical plane is controlled by microphones 5 and 6 and associated apparatus. These two microphones are placed as shown in Figures 5 and 6, near the head of the torpedo, one on the top surface, and the other on the under surface. Microphone 5 is on the top surface. The operation of this portion of the circuit of Figure 1 is substantially as follows:

Microphone 5 excites tube 15 which is biased by battery 35. Microphone 6 excites tube 16 which is biased by battery 25. The plate circuit of tube 15 includes resistance 65, battery 36, and the audio filter consisting of choke 45 and condenser 46. The plate circuit of tube 16 includes resistance 66, battery 36, and the audio filter consisting of choke 45 and condenser 46. Microphones 5 and 6 have equal sensitivities and outputs, and tubes 15 and 16 are identical. Assuming that resistances 65 and 66 are adjusted to be equal, when sounds of equal intensity reach microphones 5 and 6, the plate currents of tubes 15 and 16 are equal. Since resistances 65 and 66 are made equal, equal voltage drops occur across them due to the currents flowing through them.

The grid circuit of tube 25 consists of battery 55, and both resistances 65 and 66, as shown. The grid circuit of tube 26 consists of battery 56 and both resistances 65 and 66. The potentials of batteries 55 and 56 are alone sufficient to bias their respective tubes to cut-off, or to the point where no or very little plate current flows. Relay 50 is energized when plate current flows in tube 25, and relay 60 is energized when plate current flows in tube 26, plate potential being supplied tubes 25 and 26 by plate batteries 75 and 76 respectively. When relay 50 is energized, contact e closes, energizing magnets 8 and 10 through battery 85, and moving the rudder 98 downward as previously explained, causing the torpedo to turn downward. When relay 60 is energized, contact g closes, energizing magnets 7 and 9 through battery 85, and moving the rudder upward, causing the torpedo to turn upward. (See Figures 7 and 8.)

Assuming now that the sound approaches from the same plane in which the torpedo is already moving. It reaches microphones 5 and 6 in equal intensities, causing equal plate currents in tubes 15 and 16 and equal voltage drops across resistances 65 and 66. The voltage drop across resistance 65 tends to put a negative potential on the grid of tube 25, while the voltage drop across resistance 66 tends to apply a positive potential to the grid of tube 25. These voltage drops being equal and opposite in polarity, no effective voltage is introduced into the grid circuit of tube 25, which remains biased to cut-off by battery 55, and no plate current flows. Similarly, the voltage drop across resistance 66 tends to put a negative potential on the grid of tube 26, while the voltage drop across resistance 65 tends to put a positive potential on the grid of tube 26. These voltage drops being equal and of opposite polarity, no effective voltage is introduced into the grid circuit of tube 26, which remains biased to cut-off, and no plate current flows.

For example, assume that when the sound was reaching microphones 5 and 6 in equal intensity, the peak plate currents of tubes 15 and 16 were 10 milliamperes each. If resistances 65 and 66 are of 1000 ohms each, the peak voltage drops across each would be 10 volts. Assume now that the sound source moves downward out of the plane of motion of the torpedo, and reaches microphone 6 with greater intensity than microphone 5. As a result of this the plate current of tube 16 becomes 12 milliamperes, while that of tube 15 falls to 8 milliamperes. The voltage drop across resistance 66 will now be 12 volts, while that across resistance 65 will be 8 volts. These voltage drops are applied to the grid circuits of tubes 25 and 26. The effective voltage introduced into the grid circuit of tube 25 is 12 positive minus 8 negative, or 4 peak volts of added positive potential or between 1 and 2 volts average, reducing the bias of tube 25 to less than cut-off, causing plate current to flow, energizing relay 50, causing contact e to close, energizing magnets 8 and 10, and causing the rudder to move down, causing the torpedo to turn downward.

Under the same conditions mentioned above, when the voltage drop across resistance 66 was 12 volts, and that across resistance 65 was 8 volts, the effective voltage added in the grid circuit of tube 26 would be 4 peak volts of negative potential, increasing the bias of that tube beyond cut-off, and not energizing relay 60.

Similarly, if a sound came from above the plane of motion of the torpedo, it would reach microphone 5 in greater intensity, causing current to flow in tube 26, energizing relay 60, causing contact g to close, and energizing magnets 7 and 9 through battery 85, causing the rudder 98 to turn upward, causing the torpedo to move upward.

Resistances 65 and 66 are made variable to permit of slightly unbalancing the circuit. If the torpedo were operating in shallow water, the normal reflection of sound from the bottom or bed of the channel, lake, or stream, might cause the sound from any source within the water to reach microphone 6 in slightly greater intensity than microphone 5. This effect can be compensated for by making resistances 65 and 66 slightly unequal in value.

Relays 50 and 60 each have a second set of contacts, d on relay 50 and f on relay 60. These contacts d and f are connected in parallel. The

torpedo as disclosed may be modified by the inclusion in it of a device operated by water pressure to determine that the torpedo will travel at a certain distance under water, or at a certain depth under the surface. At 28 is shown an electrically operated device for rendering inoperative the depth-setting mechanism. 28 is energized through battery 19 by contacts *a* or *f*, so that the torpedo may move upward or downward freely in response to differences in sound intensities reaching microphones 5 and 6.

Three audio frequency filters are shown in the circuit, at 41 and 42, 43 and 44, and 45 and 46. These filters are included to minimize the effect upon the apparatus of the sound emanating from the torpedo's own engine and propeller, and consist of parallel resonant circuits predesigned to be resonant at the dominant sound frequency of the engine. Since choke coils 41 and 43 carry the filament currents of tubes 21, 22, 23, and 24 as shown, they have low resistance windings. A further means of compensating for the sound of the torpedo's engine is to increase the bias of tubes 11 and 12, and of tubes 13 and 14, and of tubes 15 and 16 or any of the other tubes of Figure 1 to the point where the sound of the torpedo's own engine is not sufficient to cause substantial plate current increases, and only when an extraneous sound is added will the amount of plate current be sufficient to operate the controlling mechanism. It is contemplated that the various batteries will be pre-designed to supply the correct potentials to bias all tubes as desired.

Relay 77 when energized closes contacts *h*, *j*, *k*, and *l*, lighting all the filaments of the various tubes in Figure 1. Battery 34 supplies the filament current for tubes 11, 21, 12, 22, 13, 23, 14, and 24. Battery 31 supplies tube 25, battery 38 supplies tube 26, and battery 39 supplies tubes 15 and 16. Relay 77 is energized as a result of the operation of the selector and "listening" circuits of Figure 2, to be subsequently explained, wires XX in Figure 1 being connected to wires XX in Figure 2.

Relay 77, and all other relays shown in the drawings and mentioned in the specification, unless otherwise stated, are of the conventional type, in which the armature is normally held away from the relay core by spring pressure until the relay is energized, when the armature moves toward the relay core, making or breaking contact, or both, as the case may be. When the relay is de-energized, the relay armature swings back to its former position.

A switch 57 is included in the grid circuit of tubes 15 and 16, for making the vertical control rudder mechanism inoperative if it is desired that the torpedo respond only to surface targets. A switch 215 is provided as shown for short-circuiting the winding of relay 77 so that none of the filaments of the tubes of the sound-sensitive steering control circuits may be lit. As was previously stated, the torpedo is designed to have general utility, so that it may be fired from a torpedo tube aimed at its target, just as an ordinary torpedo is fired. In this event, no sound steering control is necessary or desirable. Switch 216 when opened breaks the circuit to winding *n* of relay 30, rendering the microphones 3 and 4 impotent to influence the action of the torpedo, but leaving the control functions of microphones 1 and 2 unimpaired. It is contemplated that the torpedo may be fired from a torpedo tube in the general direction of its target, but not aimed exactly. Microphones 1 and 2 pick up the sound

of the target, and steer the torpedo toward it, as previously explained. Microphones 3 and 4 are rendered impotent by opening switch 216, so that the direction of the torpedo will not be influenced by the sounds coming from the submarine or vessel discharging it, and so that the torpedo will not turn and destroy the vessel or craft firing it. As will be explained subsequently, when the torpedo is fired from a torpedo tube, a latch switch on the outside of the torpedo is tripped, energizing relay 77 if switch 215 is open. By the time the filaments of the tubes of Figure 1 have heated to normal emission, the torpedo has moved some distance from the vessel firing it.

Refer now to Figure 2, a selector and discriminating circuit. One use of the invention disclosed herein contemplates that the torpedo may be moored at a desired point, and left until an enemy vessel comes within range of its sound apparatus, when the torpedo will release itself from its mooring, and proceed to its target. During this inactive period, it is essential that as little current as possible be drawn from the batteries in the torpedo. For that reason, in the present invention, a separate non-directional microphone is included, associated with a vacuum tube which may remain turned on all the time, the filaments of the tubes of the rest of the rudder control mechanism being turned off. When the "listening" microphone detects a sound, a sound which the discriminating circuit will allow to operate the proper relays, the filaments of the other tubes associated with the directing microphones are lit, the power to the motor driving the propeller is turned on, and the torpedo is released from its mooring.

The microphone 21 is placed upon the bottom of the torpedo as shown in Figure 6. It delivers its output to tube 58 of Figure 2, which is biased by battery 49 to act as a rectifier. Tube 58 is normally biased by battery 49 so that without excitation of microphone 21, the plate current is insufficient to energize and operate relay 69 when switch 204 is closed. Plate potential is supplied to tube 58 by battery 68, and filament potential by battery 67. Included in the filament circuit is switch 59, which permits the filaments of both tubes 58 and 60 to be turned off and on.

The circuit comprising tube 60 is essentially an electronic timing means. Relay 69 has three sets of contacts, *o*, *p*, and *q*, so arranged that *q* makes contact when the relay is energized, while *o* and *p* break contact when the relay magnet is energized. When the magnet is de-energized, the armature returns to its original position as explained previously. The spacing of the contact points determines that *p* breaks a fraction of a second before *q* makes. Relay 70 has two sets of contacts *r* and *s*, *r* having one armature which makes contact with two points, one when the relay is energized, and the other when it is de-energized. Relay 82 has one armature which makes contact with two points, depending upon whether the relay is energized or de-energized. As previously stated, all the relays shown in the drawings and mentioned in the specification are the conventional type unless otherwise stated, in which the armature is normally held away from the relay core by spring tension, moving toward it when the relay is energized, and moving away from it when the relay is de-energized. Relay 88 has two contacts *t* and *u*, which are latched closed by the latch 87 so that when relay 88 is de-energized, contacts *t* and *u* do not break until the latch is tripped by energization of the latch-

tripping coil 86. A switch 203 is provided for shorting contact *u*. Relay 89 has two contacts *v* and *w*, both of which make when the relay is energized, and open when it is de-energized.

At 47 is shown a light-sensitive device which may be a photo-conductive cell, which, when light reaches a certain intensity, energizes sensitive relay 48 through battery 40. A switch 29 is included for rendering the light-sensitive circuit inoperative when desired. When relay 48 is energized, it breaks the relay contacts opening the circuit of microphone 27, and rendering the selector and listening mechanism inoperative. The light-sensitive cell 47 is mounted on the outside of the torpedo as shown in Figures 5 and 6.

The operation of the circuit of Figure 2 is substantially as follows: When switch 29 is open, switch 202 is open, switch 203 is open, switch 201 is closed, and switch 59 is closed, microphone 27 picks up a sound, causing plate current to flow in tube 58 and relay 69 is energized. Contact *q* closes, permitting current from battery 84 to flow through resistance 79 charging condenser 78. If the sound continues unbroken for a sufficient time, condenser 78 is sufficiently charged to place a sufficient voltage on the grid of tube 80 to permit the requisite plate current to flow in tube 80 to energize relay 88, the elapsed time depending upon the value of the resistance 79 and the capacity of 78, for a given value of battery 84. If the sound doesn't continue for a sufficient time to operate relay 88 as above, when relay 69 is de-energized, contact *p* makes, discharging by shorting through the lower point of contact *r* and contact *s* of relay 70 the condenser 78, so that when the sound begins again, the charging process will have to start from zero again. This timing mechanism is provided so that the torpedo will not respond to the sound of thunder, gun fire, or aeroplanes flying overhead, but will respond to a sustained sound such as a ship's engines.

Assuming that the sound has continued for the required time, and relay 88 has been energized. Contact *u* is made, and if the circuit containing contact *u*, relay 89, battery 96, relay 71 (Figure 1) and the contacts of relay 172 in Figure 3, and connected by wires TT in Figures 2 and 3, is not broken due to the energization of relay 172 by the radio controlled apparatus shown in Figure 3, then relay 71 is energized and the filaments of the rudder control mechanism of Figure 1 are lit, setting these circuits in operation, and relay 89 is energized, closing contacts *v* and *w* which complete the battery circuits supplying power to 99 and 100. 99 is an electrically operated valve for turning on the compressed air or other power to the motor driving the propeller, and keeping it on as long as contact *w* remains closed. This electrically operated valve, shown in Figure 9, may be of any desired design, and may consist of a cylinder or rod which is normally held by spring tension in such a position that it closes the port, with a magnet arranged to move the rod when energized.

At 100 in Figure 2 is shown a magnet, part of an electrically operated device for releasing the torpedo from its mooring, shown in detail in Figures 14 and 15. This magnet is energized when contact *v* of relay 89 is closed.

When relay 88 is energized, contact *t* is also made, and latch 87 closes, so that contacts *t* and *u* remain closed when relay 88 is de-energized. Contact *t* closes the circuit energizing relays 70, 72, and 82 through battery 83. As a result of

these energizations, the armature of relay 82 makes contact with the inside or left-hand contact point, connecting the output of tube 80 to the latch-tripping coil 86. The contacts of relay 72 should be faster than those of relay 82. The contacts of relay 72 close, connecting condenser 74 in parallel with condenser 78 and thereby increasing the time period of the electronic time delay circuit. At relay 70, contact *s* is broken, and the armature of *r* makes contact with the inside or upper point. The effect of these contacts making and breaking at relay 70 is to convert the circuit of tube 80 into a time delay relay which is responsive to the de-energization of relay 69.

When relay 69 is de-energized, contact *o* is made, sending the charging current of battery 84 through resistance 79 until condensers 78 and 74, now in parallel, are charged sufficiently to permit enough plate current to flow in tube 80 to excite coil 86, tripping the latch 87, and opening contacts *t* and *u*.

Switch 201 when opened disconnects the plate of tube 58 from relay 69, and the switch 202 is provided for connecting the output of tube 58 directly to relay 88, so that any time delay between the picking up of the sound by microphone 27 and the energization of relays 71 and 89 through the closing of contact *u* of relay 88, is avoided. If the torpedo were to be dropped from a plane directly over an enemy ship in motion, it would be desirable that the torpedo proceed toward its target immediately after striking the water. Switch 203 bridging contact *u* of relay 88 is provided for shorting out the listening mechanism, so that the direction control apparatus may be turned on instantly. The switch 203 is a latch switch on the outside of the torpedo, designed to be tripped closed as the torpedo is discharged from a regular torpedo tube.

Figure 3 shows the device responsive to radio signals for rendering the torpedo temporarily inoperative, so that a friendly ship, by sending out the required radio transmissions, might traverse an area in which the torpedoes had been moored without harm.

Two antennae are provided on the outside of the torpedo at 105 and 106 as shown in Figure 5, consisting of insulated wires running along the surface of the torpedo. Figure 3 shows the connections of these antennae, antenna 105 delivering its output to the tuned circuit consisting of inductance 123 and condenser 125, and antenna 106 delivering its output to the tuned circuit consisting of inductance 124 and condenser 126. At 127 is a double-triode vacuum tube acting as a rectifier, and having a filament, two grids 136 and 137, and two plates 135 and 138. The grid 136 is connected to one side of tuned circuit 123—125, and the other side of this tuned circuit is connected to the filament of tube 127. The grid 137 is connected as shown to one side of the tuned circuit 124—126, the other side of this tuned circuit being connected to the filament of tube 127. Plate 135 is connected to a radio frequency filter consisting of choke 128 and by-pass condensers 129 and 130, the center or common connection of the by-pass condensers being connected as shown to the filament of tube 127. The equal resistances 131, 132, and 134, and audio frequency choke coil 133 comprise a bridge circuit, which will be unbalanced except at that audio frequency which makes the impedance of choke 133 equal to the resistance of the three resistances. Two leads are taken from the centers of the bridge as shown, and through switch 120

75 of the bridge as shown, and through switch 120

are connected to the coil of relay 153 as shown, energizing this relay when a sufficient difference of potential exists within the bridge.

Similarly, plate 138 of vacuum tube 127 is connected to a radio frequency filter consisting of choke 141 and by-pass condensers 139 and 140, the center or common connection of the by-pass condensers being connected as shown to the filament of tube 127. The equal resistances 142, 143, and 145, and audio frequency choke coil 144 comprise a bridge circuit, which will be unbalanced except at that audio frequency which makes the impedance of choke 144 equal to the resistance of the three resistances 142, 143, and 145. Two leads are taken from the centers of the bridge as shown, and through switch 119 are connected to the coil of relay 154, energizing this relay when a difference of potential exists within the bridge.

The relay 150 is a differential relay designed to operate and influence contacts A, B, and C only when the current in either one of its windings exceeds that in the other. The plate current of plate 135 of tube 127, in flowing through its radio frequency filter and audio frequency bridge as shown, flows through the upper winding M of relay 150. The plate circuit of plate 135 is thence completed through the winding of relay 152 and plate battery 147, and thence to the filament of tube 127. The plate current of plate 138 of tube 127, in flowing through its radio frequency filter and audio frequency bridge as shown, flows through the lower winding N of relay 150. The plate circuit of plate 138 is thence completed through the winding of relay 151 and plate battery 147, and thence to the filament of tube 127. Relays 151 and 152 make contact when they are energized, while relays 153 and 154 break contact when they are energized. Battery 146 supplies the filament potential for tubes 127 and 158 as shown, and may be cut out of the circuit by switch 169.

Tube 158 is an electronic time delay circuit whose time constant is determined by the values of resistance 148 and condenser 151. Battery 149 supplies the charging potential, the current from which flows through resistance 148, the contacts of relays 154, 153, 152, 151, and 150 at contact C. Tube 158 has its plate connected to the armature of relay 164, which is normally held by spring tension against the lower contact, so that plate current of tube 158 flows through relay 168 and plate battery 165, with the result that when the voltage on condenser 157 has built up sufficiently, sufficient plate current flows in tube 158 to energize relay 168. When the armature of relay 164 is against the upper contact due to the energization of the relay winding, the plate of tube 158 is connected to coil 167, as shown.

The relay 168 has three sets of contacts, F, G, and H, all of which make when the relay is energized. A latch 170 is provided so that the contacts are not broken when the relay is de-energized. Two tripping coils 166 and 167 are provided, the energization of either of which will release the latch, opening all three contacts. One tripping winding 167 is designed to be energized by the plate current of tube 158 when the armature of relay 164 is held in an upward position due to the energization of relay 164 as previously described. The other tripping coil 166 is energized through battery 163 when the contacts of time delay relay 162 are closed. Time delay relay 162 may be of any desired type, and may depend for its time delay action upon the movement of

air. The circuit for energizing time delay relay 162 includes contact A of relay 150, battery 160, and contact G of relay 168.

The contact F of relay 168 when closed energizes relays 159 and 164 through battery 161, as shown.

The function of contact H of relay 168 will be disclosed subsequently.

Relay 159 has two sets of contacts, as shown, contact D breaking when the relay is energized, and contact E making when the relay is energized. Contact E when closed connects condenser 156 in parallel with condenser 157. Condenser 156 is somewhat smaller in capacity than condenser 157, the exact capacity depending upon a time factor to be disclosed subsequently. Contact D of relay 159 influences the circuit in a manner to be subsequently explained.

Relay 150 has three sets of contacts. Contact 20 A breaks when the relay is energized. Contact B breaks when the relay is energized. In the 25 third set of contacts C, the armature makes contact with two points, one point when the relay is energized, and the other point when the relay is de-energized.

The contact H of relay 168 when closed energizes relay 172 through battery 171, which remains energized as long as contacts H remain closed. When relay 172 is energized, its contacts 30 break, breaking the circuit of Figures 1 and 2 which consisted of relay 11, battery 96, contact u of relay 88, and relay 89. The result of breaking this circuit is that the filaments of the tubes of the sound steering control are turned off, and 35 the power to the propeller is turned off at 99. If switch 204 is closed, magnet 196 is also energized through battery 171 when contact H of relay 168 is closed. Magnet 196 when energized operates a mechanism which renders the fuse of 40 the torpedo inoperative, as subsequently disclosed, and as shown in Figure 16.

Having traced the various circuits associated with tube 158, the operation of the circuits of Figure 3 can be best understood in reference to 45 the purpose of the circuit, which is to provide a means whereby a ship, by sending out a continuous radio signal or signals, can render the torpedo driving and steering mechanism, and fuse, inoperative. To accomplish this, the radio signals must result in the energization of relay 168, but must not energize tripping coils 166 or 167. Another purpose is to provide means which are to a degree secret and difficult to analyze by an 50 enemy. To accomplish this latter purpose, means are provided for discriminating between radio signals with respect to amplitude, with respect to modulation, and with respect to time, so that only signals having predetermined qualities will 55 operate the relays properly.

Assuming switches 169, 119, and 120 closed, and 60 121 and 122 open, amplitude discrimination is accomplished by differential relay 150, which is 65 designed to operate only when the current in one of its windings exceeds substantially that in the other. The upper winding M is energized by the plate current of plate 135 of tube 127, and is proportional to the intensity of the signal received on antenna 105, in accordance with well established and known laws of radio frequency rectifying 70 circuits. Similarly the lower winding N of relay 150 is energized by the plate current of plate 138 of tube 127, and is proportional to the intensity or amplitude of the signal received on antenna 106. The reason two signals are necessary under 75 the conditions specified (that is, switches 121 and

122 open) is that two other relays, namely, 151 and 152, must be energized simultaneously with relay 150, and contacts closed, if the subsequent timing circuit of tube 158 is to function properly, since the contacts of relays 151 and 152 are in the circuit of resistance 148 and condenser 157. Relay 151 is energized by the plate current of plate 138, and relay 152 is energized by the plate current of plate 135. Switch 121 is provided for shorting the contacts of relay 151, and switch 122 is provided for shorting the contacts of relay 152. When both these switches are closed, neither relay 151 or 152 need be energized to complete the circuit 149—148—157. Since relay 150 will operate contacts A, B, and C when only one antenna is furnishing a signal, this switch arrangement will permit of some secrecy, for the timing circuit of tube 158 is designed to respond only to dashes and spaces having definite time relationships, and one dash might be sent on one wavelength to antenna 105, and the next dash on the other wavelength to antenna 106, and so on, making it difficult for the enemy to analyze the required transmission and discover the "secret" code, especially so since the dashes after the first dash do not need to be of any exact length, so long as they are less than a certain length, and a definite time relationship is maintained between the dashes and spaces.

The modulation discriminating function is accomplished by the two audio frequency bridges, the one in the circuit of plate 135 comprising equal resistances 131, 132, and 134, and inductance 133, and the bridge in the circuit of plate 138 comprising equal resistances 142, 143, and 145, and inductance 144. As previously explained, these bridges will be balanced only when their respective radio frequency sources of energization are modulated at audio frequencies at which the impedances of the inductances are equal to the resistances associated therewith. Assuming switches 119 and 120 closed, relay 153 will be energized when a sufficient difference of potential exists across the bridge in the plate circuit of 135, and relay 154 will be energized when a sufficient difference of potential exists across the bridge in the circuit of plate 138. Both of these relays have their contacts in the circuit of the timing mechanism (in the circuit of the grid of tube 158), and both contacts must be closed for the proper functioning of the timing circuit. Energization of either relay breaks its contacts. Hence the energization of either of the relays 153 or 154 due to modulating the radio signals at improper audio frequencies, will render the timing circuit inoperative by opening it. Switches 119 and 120 are provided for rendering the modulation discriminating circuits inoperative, if desired. When these switches are opened, relays 153 and 154 are rendered inoperative.

The timing circuit operates as follows: Assume that it is desired to provide that a continuous code signal consisting of a first dash 5 seconds long will render the torpedo inoperative. Assume that the radio signals sent are of the proper amplitude and modulated properly to pass the amplitude and modulation discriminating circuits. Then when the first dash begins, it will energize relays 150, 151, and 152. The armature of contact C of relay 150 closes with the lower point, completing the circuit containing battery 149, resistance 148, and condenser 157. The condenser and resistance are so chosen that it will take just five seconds for the condenser to charge sufficiently to put a sufficient voltage on the grid

of tube 158 to allow sufficient plate current to pass to energize relay 168.

Assume for the moment that the dash lasted only 4 seconds. Then relay 150 is de-energized when the dash ends, the armature of contact C swings back making contact with the upper point. This point is connected as shown with contact D of relay 159, which contacts are closed when the relay 159 is not energized. The armature of D of relay 159 is connected as shown to a point between battery 149 and condenser 157, with the result that when relay 150 is de-energized, condenser 157 is discharged by short-circuiting it through contact C of relay 150 and contact D of relay 159. At the same moment that the de-energization of relay 150 causes condenser 157 to be shorted and discharged, the armature of C swings away from its lower point, breaking the battery circuit of battery 149. Hence a means is provided for making the mechanism responsive to a first dash of at least a certain length.

Assume now that the dash continues for the necessary five seconds to energize relay 168. At the 5 second point, contacts F, G, and H of relay 168 are closed, and latched. Contact H energizes relay 172 as previously explained. Contact G although closed does not energize time delay relay 162 immediately, because contact A of relay 150 is broken when 150 is energized. Contact F of relay 168 energizes relays 164 and 159 through battery 161, keeping them energized until the contacts of relay 168 are unlatched. Relay 164 pulls its armature upward, connecting the output of tube 158 to the latch tripping coil 167. Relay 159 opens contact D and closes contact E which puts condenser 156 in parallel with condenser 151. There is an immediate drop in voltage across condenser 157 as a result, causing the plate current of tube 158 to fall, with the result that tripping coil 167 is not immediately sufficiently energized to trip the latch 170 of relay 168. It is essential to the proper operation of the circuits that the contacts of relay 164 be slower than those of relay 159, for condenser 156 must be connected an instant before coil 167 is connected into the circuit, otherwise the grid voltage of tube 158 would not fall, the plate current of tube 158 would not fall, and coil 167 would be energized the instant the armature of relay 164 touched the upper contact, tripping the latch of relay 168. Hence if the dash stops at five seconds, contact H of relay 168 remains closed, and the power to the torpedo remains turned off.

Assume now that the dash lasted longer than five seconds. After relay 159 has been energized, condensers 156 and 157 in parallel continue to be charged through resistance 148 until they place a sufficient voltage on the grid of tube 158 to allow sufficient plate current to flow to energize coil 167, tripping the latch, resulting in the turning on of the torpedo's power. So that the mechanism has been made responsive only to a first dash of less than a certain duration.

The circuit also operates to insure that only spaces of the proper length between dashes, will cause the power to the steering, propelling, and releasing mechanisms to remain cut off. If the spaces are either too short or too long, the power will be turned on. This is brought about in the following manner: Assuming that the dash ended after five seconds, the contacts F, G, and H of relay 168 remaining latched. When relay 150 is de-energized due to the stoppage of the signal, contact A makes, completing the circuit containing time delay relay 162 and battery 160. If the

space continues long enough, say two seconds, to energize the time delay relay 162 completely, its contacts close, energizing latch tripping coil 166 through battery 163. This trips the latch 170, resulting in the turning on of the torpedo power, and steering apparatus. But assume that the space did not last long enough to close the contact of relay 162. When contact A of relay 150 is broken at the beginning of the next dash, relay 162 returns to its normal de-energized position. Since the dash is longer than the space, any air has time to be replaced in relay 162, or temporary residual magnetism or currents to subside. Hence the space between dashes can not exceed a certain value.

If the space between dashes is not long enough, the latch will be tripped. When the dash stops, a charge remains on condensers 157 and 156. Assuming that the dash was of the correct length to energize relay 168 but not to unlatch 170, then the de-energization of relay 150 closes contact B, which connects resistance 155 across the two condensers. The value of this resistance is chosen so that it will just discharge the condensers completely in the time of the desired space. If the space is not long enough, the condensers will not be fully discharged during the space, and when the next dash begins, it will find some residual charge on the condensers, and the plate current of tube 158 will build up in less time than calculated to a value sufficient to energize coil 167 tripping the latch 170 of relay 168, resulting in the power being turned on to the torpedo motor and steering apparatus.

After the first dash, the dashes can be of any length less than the time required to trip the latch 170, provided the spaces are sufficiently long each time to discharge the condensers. The spaces can not be too long or relay 162 will operate to restore the power to the torpedo.

When the ship has passed, all that is necessary to replace the torpedo in its former condition of waiting is to stop the transmission of radio signals. The first space exceeding the time, or equaling the time, required to close the contact of relay 162 energizes coil 166 tripping the latch 170.

The effective range of the ship's radio apparatus should exceed the effective range of the torpedo's sound apparatus.

Figure 9 is a plan view of the inside of the torpedo, showing the placing of the various parts. Section K contains the explosive, section L contains the batteries and electrical equipment. Section L is so designed that batteries 67, 58, and 40 of Figure 2, and batteries 146 and 147 of Figure 3 comprise a separate compartment easily accessible. A plate may be screwed over an opening in the wall of the torpedo through which these batteries may be moved. These are the only batteries on which there will be a constant drain whether the torpedo is in operation or not, and proper biasing will reduce the drain of the plate batteries. It is contemplated that the torpedo, when moored to one spot, may be periodically "serviced," by replacing the batteries mentioned with new ones. Section P contains the tank of compressed air, and section Q contains the propeller driving motor or engine and associated apparatus. The engine may be an air-driven turbine or any convenient device. The electrically operated valve 99 joins sections P and Q, operating as previously disclosed. Section W contains the steering apparatus, shown in detail in Figures 7 and 8.

Refer now to Figures 10, 11, 12, and 13, which show views of the mechanism for attaching the torpedo to a parachute, and releasing it. In Figure 10, the lever 173 is a wide, thin lever attached to the side of the torpedo 200 as shown. Attached to the lever is a pin 174. This mechanism is attached to the torpedo on that side of its center of gravity which will determine that the torpedo in descending strikes the water from such an angle as to cause the lever 173 to move toward the right (in Figure 10). The dotted lines show the lever and pin folded into the position they will occupy after the torpedo has assumed its normal motion through the water. Figure 13 shows the 10 parachute 175, a light chain 176 attached to it, and the shackle 177 attached to the end of the chain. Figure 11 is a view of a part of the mechanism, looking along the surface of the torpedo. On the side of the torpedo are three collars 180, 181, and 182. A bolt 178 passes through these, and also through shackle 177 as shown. A spring 179 is provided which tends to eject the bolt from the collars. Figure 12 shows a section of the mechanism, showing the pin 174 passing through a loosely fitting collar 183 and into a groove cut in the bolt 178. The action of the mechanism disclosed in Figures 10, 11, 12, and 13 is substantially as follows: When the torpedo is prepared to be launched by parachute, shackle 177 is placed in position, and bolt 178 pressed against the spring 179 until the bolt passes through the collars and the shackle. The lever 173 is raised, forcing pin 174 into the groove of bolt 178, holding the bolt in position passing through the collars and shackle. When the torpedo strikes the water after descending, the force of the water moves lever 173 back, withdrawing pin 174, whereupon spring 179 causes bolt 178 to spring to the right in Figure 12, releasing the shackle.

Refer now to Figures 14 and 15, which show the method of mooring the torpedo. In Figure 15, a floating or submerged buoy 211 is attached by rope 212 to an anchor 214. Rope 206 goes from the buoy to the torpedo, and is attached by the mechanism shown in section in Figure 14. The rope 206 is attached to the eyebolt 205 which passes through two collars 198 and 199 attached to the side of the torpedo 200. Inside the torpedo, placed as shown, is iron rod 209 having a flange 207, and arranged to engage a groove in the bolt 205. The rod passes into a solenoid 100 as shown. The rod 209 is normally held in the groove of bolt 205 by the action of spring 208 as shown, but when the solenoid is energized, it pulls the rod downward or inward compressing the spring and enabling the bolt to slip out of its collars. Magnet 100 is energized from a battery as shown in Figure 2. At the same moment that the solenoid 100 is energized, the valve 99 is turned on as previously described and as shown in Figure 2, and causes the torpedo to move forward causing the bolt to slip from the collars. Figure 15 shows a side view of the torpedo, with the eyebolt 205 in place in its collars.

Refer now to Figure 16 which shows a sectional view of the contact fuse or percussion fuse mentioned previously. As was stated formerly, the torpedo is designed so that a friendly vessel, by emitting a secret radio signal or signals, may safely traverse an area in which the torpedoes had been moored. This radio wave renders the steering control apparatus and the torpedo motor inoperative as previously explained, and also renders the fuse mechanism inoperative so that if the vessel struck the torpedo from a certain

angle, it would not necessarily explode. In Figure 16, the striker head is shown at 184, to which is attached the firing pin 188. The striker head is normally held as shown by the pressure of spring 185, but when the torpedo strikes its target, the striker head is forced back or down, forcing the firing pin 188 into the primer 189, exploding the detonator 190. At 191 is shown the flash hole leading to the main charge of explosive. Attached to the side of the fuse is a solenoid 196 supported as shown on support 194. Inside the solenoid is a rod 195, normally held in the position shown by the action of spring 193. The rod is made of two parts, joined in any convenient manner. Part S is of a magnetic material, part R being of a nonmagnetic material. When solenoid 196 is energized, part S is drawn inward or to the left, forcing the rod toward the left, in which position it prevents the firing pin from moving by holding the flange 192 of the firing pin against the rib 187 of the fuse body. The solenoid 196 is energized from battery 171 as shown in Figure 3. Switch 204 is provided for cutting the solenoid out of the circuit when desired.

It is not necessary that the arcs of response of the various microphones 1, 2, 3, and 4 cover exactly that portion of the 360 degrees as shown in Figure 4. For example, the arcs of microphones 3 and 4 might extend somewhat farther forward, or the arcs of microphones 1 and 2 might extend toward the rear of the torpedo.

It is likewise not necessary that the patterns of response of microphones 1 and 2 be exactly identical, but they must provide exactly equal outputs when excited by any sound coming from directly in front of the torpedo.

It is contemplated that dynamic type microphones be used in the drawings and specification as disclosed, but it is not intended to limit the invention thereby. Where tubes 25 and 26 have been described as normally biased to cut-off, these tubes could be biased at less than cut-off, but biased at a point where sufficient plate current to operate the relays in their plate circuits flows only when a difference of sound intensities reach microphones 5 and 6.

While the various antennae, microphones, light-sensitive cell, and apparatus for attaching the torpedo to a parachute or buoy, and some of the rudders, are shown as protruding beyond the plane of the normal surface of the torpedo, it is not intended to limit the invention thereby to the use of such apparatus. These parts which now protrude might all be placed in grooves, slots, or indentations below the plane of the surface, so that the torpedo may be fired from a regular shaped torpedo tube.

It is contemplated that all of the switches except switch 203 of Figure 2 be brought to a common terminal board, either on the surface of the torpedo, or which may be reached by unscrewing a plate, so that the various desired combinations of switches may be closed or opened, depending upon whether the torpedo is to be launched by tube, parachute, or moored, and whether the light-sensitive circuit, or the listening circuit, or the radio control circuit, or other circuits or elements are to be used, and in what manner. Switch 203 of Figure 2 is a latch switch arranged to be tripped as the torpedo is shot out of its tube. It turns on the power to the torpedo propeller immediately, and, if desired, turns on the sound controlled steering apparatus immediately, after a brief interval in which the filaments of the various tubes warm up.

It is contemplated that the torpedo might be used to guard a certain shipping lane during the night, in which case it would be moored nearby. When daylight came, the light sensitive cell would render the listening microphone inoperative, and would also render the fuse inoperative, the power valve, and the mechanism for releasing the torpedo from its mooring, by in effect closing the circuit at contact H of relay 168.

Some other modifications of the circuits are possible. Where many separate batteries are now shown, in some instances one battery could supply many circuits.

Figure 3 may be modified to include additional relays corresponding to relays 151 and 152 responsive to any desired number of different radio transmissions on different wavelengths. One additional winding on relay 150 may be provided for each additional wavelength. In this way, the proper operation of the timing circuit of tube 158 would be made dependent on simultaneous transmissions on more than two wavelengths, or, if all the contacts of the additional relays were shorted by closing switches corresponding in function to switches 121 and 122, relay 150 being responsive to transmissions on any one of the wavelengths, the series of dashes required to maintain the contacts of relay 168 closed could be sent on more than two alternate wavelengths, making it more difficult for an enemy to discover the secret of the transmissions.

Other modifications are possible, and I therefore do not wish to be limited to the precise details of the invention as set forth herein, except as required by the claims which follow.

I claim:

1. In a torpedo, steering apparatus comprising rudders and moving means for turning said rudders, control means for said moving means adapted to be electrically operated, a source of power for said control means, a pair of microphones, a first relay having a pair of windings each carrying current substantially proportional to the intensity of sound reaching one of said pair of microphones, a third microphone, a second relay having a first winding and a second winding, the first winding of said second relay carrying a current substantially proportional to the intensity of sound reaching said third microphone, the second winding of said second relay carrying current proportional to the intensity of sound reaching at least one of said pair of microphones, the contacts of said first and said second relays controlling the application of said source of power to said control means.

2. In a torpedo, steering apparatus comprising rudders and moving means for turning said rudders, control means for said moving means adapted to be electrically operated, a source of power for said control means, a pair of microphones, a thermionic rectifier associated with each microphone of said pair wherein the rectified current is substantially proportional to the intensity of sound reaching the microphone associated therewith, resistance means connected with each of said rectifiers, relay means, means rendering said relay means controlled by differences in potential existing across said resistance means, the contacts of said relay means controlling the application of said source of power to said control means.

3. In a torpedo, apparatus for steering comprising a first rudder mechanism for turning the torpedo in a horizontal plane, a second rudder mechanism for turning the torpedo in a vertical plane, first and second moving means for turning said rudder mechanisms, first and second control

means for said moving means adapted to be electrically operated, at least one source of power for said first and second control means, a first pair of microphones, a first relay having a pair of windings each carrying current substantially proportional to the intensity of sound reaching one of said first pair of microphones, a third microphone, a second relay having a first winding and a second winding, the first winding of said second relay carrying a current substantially proportional to the intensity of sound reaching said third microphone, the second winding of said second relay carrying current proportional to the intensity of sound reaching at least one of said first pair of microphones, the contacts of said first and said second relays controlling the application of said source of power to said first control means; a second pair of microphones, a thermionic rectifier associated with each microphone of said second pair wherein the rectified current is substantially proportional to the intensity of sound reaching the microphone associated therewith, resistance means connected with each of said rectifiers, relay means, means rendering said relays means controlled by the differences in potential existing across said resistance means, the contacts of said relay means controlling the application of said source of power to said second control means.

4. In a torpedo, the combination of rudders, moving means therefor electrically operated; a plurality of microphones, a first electric circuit normally inoperative including at least one thermionic tube connecting said microphones with said moving means whereby said rudders are adapted to be moved in response to sounds reaching said microphones, at least one source of power for said thermionic tube, and a second electric circuit energized directly from one of said microphones including means for controlling the application of said source of power to said thermionic tube whereby sounds actuating said second electric circuit cause said first electrical circuit to become operative to control said rudders.

5. In a torpedo having propelling and steering mechanism, means for attaching the torpedo to an object external thereto comprising a first member adapted to catch with a suitable adjacent external member, a solenoid adapted to release said first member when the solenoid is energized, a source of power for said solenoid, a circuit connecting said source of power and said solenoid, a relay, the contacts of said relay being in the said circuit of the source of power and solenoid, said relay acting when energized to apply power to said solenoid, a microphone, and means rendering said relay energized upon the receipt of sounds of at least a predetermined duration by said microphone to close said circuit and release said torpedo.

6. In a torpedo having steering means, propelling means and a source of power for said propelling means, electrically operated control means for starting said propelling means and a source of power for said electrically operated control means; means for attaching the torpedo to an object external thereto comprising a first member adapted to catch with a suitable external member, a solenoid adapted when energized to release said first member, a source of power for said solenoid, a relay having contacts which close when the relay is energized the contacts of said relay controlling the application of power to said propeller control means and the applica-

tion of power to said solenoid, a microphone, and means rendering said relay energized upon the receipt of sounds of at least a predetermined duration by said microphone to effect the starting of the propelling means and the releasing of the torpedo.

7. In a torpedo, rudders, moving means electrically operated for turning said rudders, relay means for controlling said moving means, a plurality of microphones disposed on said torpedo and adapted to be actuated by sounds reaching said torpedo from an external source, means rendering said relay means actuated by differences in sound intensity reaching pairs of said microphones to effect the steering of the torpedo, said last mentioned means including at least one thermionic tube and at least one source of power for said tube, a first relay, the circuit of said thermionic tube and said source of power including the contacts of said first relay, said first relay acting when energized to close its contacts, a source of power for said first relay, a second relay and a third relay, the circuit of said last mentioned source of power and said first relay including the contacts of said second relay and the contacts of said third relay, said second relay acting when energized to close the circuit supplying power to said first relay, said third relay acting when energized to open the circuit supplying power to said first relay, means rendering said second relay actuated by sounds reaching one of said microphones to cause the energization of said first relay and the application of power to said thermionic tube, radio receiving means, means rendering said third relay actuated by said radio receiving means to open the circuit supplying power to said first relay, whereby when said radio receiving means is energized by a radio signal of predetermined character, sounds reaching said torpedo are prevented from causing the application of power to said thermionic tube.

8. In a torpedo, propelling means, a source of power for said propelling means, electrically operated control means for starting said propelling means including a first relay, said first relay acting when energized to start said propelling means, a source of power for said first relay, a second relay and a third relay, an electrical circuit connecting said source of power with said first relay including the contacts of said second relay and the contacts of said third relay, said second relay when energized acting to close its contacts, said third relay when energized acting to open its contacts, a microphone, means rendering said second relay energized when sounds of at least a predetermined duration reach said microphone, radio receiving means, and means rendering said third relay energized when said radio receiving means are energized by a radio signal of predetermined character.

9. In a torpedo having propelling and steering mechanism, means for attaching the torpedo to an object external thereto comprising a first member adapted to catch with a suitable adjacent external member, a solenoid adapted when energized to release said first member, a source of power for said solenoid, a circuit connecting said source of power and said solenoid, a first relay, the contacts of said first relay being in the circuit of said solenoid and said source of power, said first relay acting when energized to close its contacts, a source of power for said first relay, a second relay and a third relay, an electric circuit connecting said source of power with said first relay including the contacts of said second

relay and the contacts of said third relay, said second relay when energized acting to close its contacts, said third relay when energized acting to open its contacts, a microphone, means rendering said second relay energized when sounds of at least a predetermined duration reach said microphone, radio receiving means, and means rendering said third relay energized when said radio receiving means are energized by a radio signal of predetermined character.

10. In a torpedo having steering means, propelling means and a source of power for said propelling means, electrically operated control means for starting said propelling means and a source of power for said electrically operated control means; means for attaching the torpedo to an object external thereto comprising a first member adapted to catch with a suitable external member, a solenoid adapted when energized to release said first member, a source of power for said solenoid, a first relay, the contacts of said first relay closing when the relay is energized and applying power to said propeller control means and to said solenoid, a source of power for said first relay, a second relay and a third relay, an electric circuit connecting said source of power with said first relay including the contacts of said second relay and the contacts of said third relay, said second relay when energized acting to close its contacts, said third relay acting when energized to open its contacts, a microphone, means rendering said second relay energized when sounds of at least a predetermined duration reach said microphone, radio receiving means, and means rendering said third relay energized when said radio receiving means are energized by a radio signal of predetermined character, whereby sounds reaching said microphone are ineffective to release and start the torpedo when the relay responsive to said radio receiving means is being energized.

11. In a torpedo, rudders, moving means for turning said rudders, a source of power for said moving means, relay means controlling the application of said source of power to said moving means, a plurality of microphones, means for energizing said relay means in response to sounds reaching said microphones to effect the steering of the torpedo, said last mentioned means including at least one thermionic tube and at least one source of power for said tube, a light-sensitive device, and a relay actuated from said light-sensitive device, said relay acting when energized to open the circuit connecting said thermionic tube and said source of power, whereby light reaching said light-sensitive device in predetermined intensity prevents sounds reaching said microphone from moving said rudders.

12. In a torpedo, propelling means, a source of power for said propelling means, electrically operated control means for starting said propelling means, including a first relay, said first relay acting when energized to start said propelling means, a source of power for said first relay, a second relay and a third relay, an electric circuit connecting said source of power with said first relay including the contacts of said second relay and the contacts of said third relay, said second relay when energized acting to close its contacts, said third relay acting when energized to open its contacts, a microphone, means rendering said second relay energized when sounds of at least a predetermined duration reach said microphone, a light-sensitive device, and means rendering said third relay energized when said

light-sensitive device is receiving light of predetermined intensity.

13. In a torpedo, propelling mechanism, control means electrically operated including a first relay for starting said propelling mechanism, a microphone and a circuit associated therewith for energizing said first relay in response to sounds reaching said microphone to effect the starting of the propelling mechanism, a light-sensitive device and a second relay having its energization controlled by said light-sensitive device and having at least one contact in the circuit of said microphone, whereby the energization of said second relay due to light reaching said light-sensitive device in predetermined intensity prevents sounds reaching said microphone from starting the said propelling mechanism.

14. In a torpedo having propelling and steering mechanism, means for attaching the torpedo to an object external thereto comprising a first member adapted to catch with a suitable adjacent external member, a solenoid adapted when energized to release said first member, a source of power for said solenoid, a circuit connecting said source of power and said solenoid, a first relay, the contacts of said first relay being in the circuit of said solenoid and said source of power, said first relay acting when energized to close its contacts, a source of power for said first relay, a second relay and a third relay, an electrical circuit connecting said source of power with said first relay including the contacts of said second relay and the contacts of said third relay, said second relay when energized acting to close its contacts, said third relay when energized acting to open its contacts, a microphone, means rendering said second relay energized when sounds of at least a predetermined duration reach said microphone, a light-sensitive device and means rendering said third relay energized when light reaches said light-sensitive device in predetermined intensity.

15. In a torpedo having steering means, propelling means and a source of power for said propelling means, electrically operated control means for starting said propelling means and a source of power for said electrically operated control means; means for attaching the torpedo to an object external thereto comprising a first member adapted to catch with a suitable external member, a solenoid adapted when energized to release said first member, a source of power for said solenoid, a first relay having contacts which close when the relay is energized, the contacts controlling the application of power to said propeller control means and the application of power to said solenoid, a source of power for said first relay, a second relay and a third relay, an electric circuit connecting said source of power with said first relay including the contacts of said second relay and the contacts of said third relay, said second relay when energized acting to close its contacts, said third relay acting when energized to open its contacts, a microphone, means rendering said second relay energized when sounds of at least a predetermined duration reach said microphone, a light-sensitive device, and means rendering said third relay energized when said light-sensitive device is receiving light of predetermined intensity whereby sounds reaching said microphone are ineffective to release and start the torpedo when the relay responsive to said light-sensitive device is being energized.

16. In a torpedo, steering means and electrically

operated control means therefor, propelling means and electrically operated control means for starting said propelling means, a plurality of microphones, an electrical circuit normally operative connecting said microphones and both of said control means to effect the starting of the torpedo upon the receipt of sounds by at least one of said microphones and the guiding of the torpedo by sounds reaching a pair of said microphones, and radio controlled means for rendering said electrical circuit inoperative upon the receipt of radio signals of predetermined duration, said last mentioned means including a radio receptive device and an electronic time-delay relay.

17. In a torpedo, steering means and electrically operated control means therefor, propelling means

5 and electrically operated control means for starting said propelling means, a plurality of microphones, an electrical circuit normally operative connecting said microphones and both of said control means to effect the starting of the torpedo upon the receipt of sounds by at least one of said microphones and the guiding of the torpedo by sounds reaching a pair of said microphones, and radio controlled means for rendering said electrical circuit inoperative upon the receipt of radio signals of predetermined character including an audio frequency bridge circuit and apparatus associated therewith adapted to be operated when said bridge is unbalanced.
